UNITED STATES PATENT OFFICE

RICHARD M. WILDBERG, OF CINCINNATI, OHIO, ASSIGNOR, BY MESNE ASSIGNMENTS, TO UNITED MILK CRATE CORPORATION, OF CINCINNATI, OHIO, A CORPORATION OF OHIO

CORNER IRON FOR BOXES

Application filed June 17, 1926. Serial No. 116,680.

My invention relates to devices for protecting the corners of boxes and crates, and particularly for boxes which are intended to be stacked one on the other, in which an upwardly projecting shoulder is provided for the inside of the corner to serve as a guide and to prevent the boxes from sliding on each other when stacked.

It has been usual to provide separate stacking irons, which are merely nailed to the top of the box at the corners, or if inside flanges are employed, nails have also been used, so that under the strain to which the stacking irons are subjected, they frequently become loose or are broken off, or the wood is split by the nails.

It is the object of my present invention to provide such stacking irons formed from an integral blank of sheet metal so bent and formed, that depending flanges may be provided for both the inside and outside of the corner, and that a metal to metal portion is provided for double riveting which shall retain the iron in position, even in the event of one of the rivets giving away, and in which a very strong and effective corner stacking iron is provided at a minimum expense.

As the invention relates to the corner iron construction alone, I have not thought it necessary to illustrate an entire box, it being understood that the device is applicable to each of the four corners of any open top construction of box.

In the drawings:—

Figure 1 is a plan view of the blank from which the corner iron is constructed.

Figure 2 is a perspective view of the corner iron as mounted on one of the corners of the box.

Figure 3 is a front elevation from the outside of the corner iron.

Figure 4 is a similar view from the inside.

A blank of suitable sheet metal is cut as shown in Figure 1. The body of the blank 1 is designed for longitudinal folding on the dotted line 2, and for transverse folding on the line 3. The blank is cut with a slot 4 to provide a pair of tongues 5, 6 as a whole, which are designed for transverse folds on the lines 7, 8 and 9. Rivet holes 10 are also

punched at the top and bottom of the blank.

The blank is then subjected to a die press, and the two halves of the blank are folded at right angles to each other on the fold line 2, forming a right angled corner of 55 plates 11 and 12.

The tongues are then folded to bring the faces together and to form upwardly projecting portions 13 and 14, and a slight inward curve 15, 16, given on the fold lines 3 and 8 with the portions of the blank between the fold lines bent at right angles to the upstanding portion, forming horizontal portions 17, 18, and the outer ends are bent down at right angles to the portions 17 and 18, forming securing tongues 19 and 20. The tongues 19 and 20 are spaced from the body of the blank the thickness of the sides of the box.

The corner plates are then fitted to the respective corners, and rivets passed through the wood and through the holes 10, which are spaced so that they will register, and riveted in place metal to metal. Thus the corners of the wooden box are reinforced and strengthened, and as the construction is all one integral piece, even if the wood should be split on one side, or the rivet broken or displaced, the corresponding rivet through the adjoining corner will hold the device in place.

Having thus described my invention what 80 I claim as new and desire to secure by Letters Patent is:—

A corner iron for open boxes, formed substantially without waste from an integral blank of sheet metal cut and scored to fold longitudinally to form sides, with tongues integral with the sides folded to form a pair of upwardly two ply return bent projecting portions to form stacking guides and then horizontally and downwardly to fit over corners of a wooden box, with rivet openings in the respective sides and tongues for riveting metal to metal.

RICHARD M. WILDBERG.
